TOY PIANOS

Harry Zimmerman, New York, N. Y.

Application April 6, 1955, Serial No. 499,701

9 Claims. (Cl. 84—404)

My invention relates to musical toys provided with a series of differently tuned tone elements on which various melodies can be played by striking these elements successively and selectively.

Objects of my invention are to strike the tone elements with missiles propelled by a projector, thereby to produce clean tones which are not impaired by activating means, to provide an individual missile and an individual projector for each tone element, thereby to make possible the selective and alternate use of the tone elements, and thereby to make possible to play various melodies in a novel and amusing manner.

Other objects are to return the missiles to the projectors automatically, to provide channels or runways for guiding the missiles toward the tone elements and back to the projectors, and to shape the missiles so that they roll easily in these channels.

Further objects are to simulate a piano, to operate the projectors by the keys of a piano-like key board, to provide the toy with a piano-like shaped housing, to arrange the tone elements in the higher back portion of this housing and to arrange the keys near the front of this housing.

Still other objects are to use vertically extending bars as tone elements, thereby to facilitate their arrangement in the higher back portion of a piano-like housing, to suspend these tone bars pendulously whereby they will produce clean vibrations and tones under the impact of the missiles, and to prevent excessive pendulous movement of these bars.

Still further objects are to attain these objects with simple, reliable and inexpensive means, and to provide a novel musical toy that can be easily made, assembled and operated.

Still other objects and advantages will appear from the following description of an exemplifying embodiment of my invention, from the appended claims and from the accompanying drawing in which:

Fig. 1 shows a perspective view of an illustrative embodiment of my invention.

Fig. 2 shows a vertical cross-section taken along the line 2—2 in Fig. 1.

Fig. 3 shows a broken off cross-section taken along the line 3—3 in Fig. 2.

Fig. 4 shows a broken off cross-section taken along the broken line 4—4 in Fig. 2.

The shown embodiment has a housing 5 of an outer shape simulating a piano, and comprises a higher back portion 6 and a lower front portion 7 which has a top 8 sloping toward the front and side walls 9 rising higher than the top 8. A plurality of channels or runways 11 are positioned under the top 8 and extend parallel to this top into the back portion 6 of the housing. These channels may have rectangular cross-sections and walls forming integral parts of the housing.

A shaft or axle 12 extends near the front of the housing from one side wall 9 horizontally to the other. Le-

vers 13 have bores for the passage of the axle 12. Each lever is individually turnable about this axle by means of a key 14 formed with the lever as one piece. The keys 14 are shaped and arranged over the top 8 and between the side walls 9 like the keys of a piano key board.

The levers 13 reach through slots of the top 8 into the channels 11 and form projectors for ball-shaped missiles 15 positioned movably in these channels. One ball 15 and one projector 13 is provided for each channel.

10 The rear or higher end of the channels are open. Tone elements, one of which is indicated by numeral 16, extend at a small distance behind these channel ends. The channels 11 are long, and the distance of each projector 13 from the co-ordinated tone element is many times as long as the propelling movement of the projector and as the diameter of the propelled ball so that latter makes a move of considerable length between projector and tone element. The tone elements may be, for example, elongated bars extending vertically and having arc-shaped horizontal cross-sections. These tone bars are preferably suspended in the following manner:

A wall or plate 17 is affixed to the housing 5 and extends behind the bars 16 across the housing portion 6. Projections 18 extend from the wall 17 between and aside of the bars to the front. The front of the projections 18 is slotted, and a cord 19 is wedged into these slots. The cord has knots 21 at its ends and is held by those projections 18 which are adjacent to the knots 21 in tense condition. Each tone bar has a hook 22 stamped and bent out of its material. The hooks 22 engage the cord 19.

The projections 18 serve also to hold the tone bars in spaced positions along the cord 19. Excessive pendulous movement of these bars is prevented by strips 23, 24 and 25 which are made of felt or other soft cushioning material and extend at short distances from and across the tone bars. The strip 23 is affixed to a rigid strip 26 which has ends affixed to the side walls of the housing 5. If the tone bars have different lengths which is a preferred way of tuning the same differently, the strips 23 and 26 may extend obliquely according to the positions of the lower ends of the tone bars. The strip 24 is preferably positioned opposite to the strip 23 behind the tone bars and is affixed to the lower rim of the wall 17 which may extend in corresponding oblique direction. The strip 25 is also affixed to the wall 17 and extends behind the tone bars near the projections 18.

40 The musical toy operates as follows: 45 Any desired melody or sequence of tones may be played by striking the keys 14 in piano-like manner. When a key is struck down, the respective projector or lever 13 propels a ball 15 toward the co-ordinated tone bar. The impact of the ball causes the tone bar to produce a particular tone. Then, the ball rolls back in the channel 11 and comes to rest again behind the projector.

I desire it understood that my invention is not confined to the particular embodiment shown and described, the same being merely illustrative, and that my invention may be carried out in other ways within the scope of the appended claims without departing from the spirit of my invention as it is obvious that the particular embodiment shown and described is only one of the many that may be employed to attain the objects of my invention.

60 65 Having described the nature of my invention, what I claim and desire to protect by Letters Patent is:

1. In a musical toy, a series of differently tuned tone elements, a plurality of ball-shaped missiles made of solid material, each co-ordinated to one of said elements, and a plurality of projectors, each being adapted for propelling one of said missiles toward the co-ordinated

nated element being operable independently of the other projectors and having a distance from said element several times as large as the extension of said missile in the direction of propulsion whereby said propelled missile makes a move of considerable length from said projector to said element.

2. A musical toy comprising a series of differently tuned tone elements, a housing supporting said elements and having a plurality of channels, each being directed toward one of said elements, a plurality of missiles made of solid material, each rollably movable in one of said channels and thereby co-ordinated to one of said elements, and a plurality of projectors, each being positioned near the end of one of said channels which is far from the respective element, being adapted for propelling one of said missiles toward the co-ordinated element being operable independently of the other projectors and having a distance from said element several times as large as the extension of said missile in the direction of propulsion whereby said propelled missile makes a move of considerable length from said projector to said element.

3. A musical toy comprising a series of differently tuned tone elements, a housing supporting said elements and having a plurality of channels, each being directed and obliquely rising toward one of said elements, a plurality of missiles made of solid material, each rollably movable in one of said channels and thereby co-ordinated to one of said elements, and a plurality of projectors, each being positioned near the end of one of said channels which is far from the respective element, being adapted for propelling one of said missiles toward the co-ordinated element being operable independently of the other projectors and having a distance from said element several times as large as the extension of said missile in the direction of propulsion whereby said propelled missile makes a move of considerable length from said projector to said element.

4. A musical toy comprising a series of differently tuned tone elements, a housing supporting said elements and having a plurality of channels, each being directed toward one of said elements, a plurality of rollably shaped missiles made of solid material, each movable in one of said channels and thereby co-ordinated to one of said elements, and a plurality of projectors, each being positioned near the end of one of said channels which is far from the respective element, being adapted for propelling one of said missiles toward the co-ordinated element being operable independently of the other projectors and having a distance from said element several times as large as the extension of said missile in the direction of propulsion whereby said propelled missile makes a move of considerable length from said projector to said element.

5. A musical toy comprising a series of differently tuned tone elements, a housing supporting said elements and having a plurality of channels, each being directed toward one of said elements, a plurality of missiles made of solid material, each rollably movable in one of said channels and thereby co-ordinated to one of said elements, and a plurality of projectors, each being positioned near the end of one of said channels which is far from the respective element, being adapted for propelling one of said missiles toward the co-ordinated element having a key for individual operation, and having a distance from said element several times as large as the extension of said missile in the direction of propulsion whereby said propelled missile makes a move of considerable length from said projector to said element, 70 said keys being arranged in a row like the keys of a piano key board.

6. A musical toy comprising a series of differently tuned tone elements, a housing having an outer shape simulating a piano, said housing supporting said elements and having a plurality of channels, each being directed toward one of said elements, a plurality of missiles made of solid material, each rollably movable in one of said channels and thereby co-ordinated to one of said elements, and a plurality of projectors, each being positioned near the end of one of said channels which is far from the respective element, being adapted for propelling one of said missiles toward the co-ordinated element having a key for individual operation, and having a distance from said element several times as large as the extension of said missile in the direction of propulsion whereby said propelled missile makes a move of considerable length from said projector to said element, said keys being arranged in a row like the keys of a piano key board.

7. A musical toy comprising a housing, a series of differently tuned tone elements forming bars hanging vertically in said housing, a plurality of ball-shaped missiles made of solid material movable in said housing, each co-ordinated to one of said bars, and a plurality of projectors movably connected with said housing, each adapted for propelling one of said missiles toward the co-ordinated tone element and having a distance from said element several times as large as the extension of said missile in the direction of propulsion whereby said propelled missile makes a move of considerable length from said projector to said element.

8. A musical toy comprising a housing, a series of differently tuned tone elements forming bars hanging vertically in said housing, strips affixed to said housing and extending at small distances from and across said bars, a plurality of missiles made of solid material rollably movable in said housing, each co-ordinated to one of said bars, and a plurality of projectors movably connected with said housing, each adapted for propelling one of said missiles toward the co-ordinated tone element and having a distance from said element several times as large as the extension of said missile in the direction of propulsion whereby said propelled missile makes a move of considerable length from said projector to said element.

9. A musical toy comprising a housing having a shape simulating a piano and including a higher back portion and a lower front portion, a series of differently tuned tone elements forming bars hanging vertically in said back portion of said housing, a plurality of missiles made of solid material rollably movable in said housing, each co-ordinated to one of said bars, and a plurality of projectors movably connected with said front portion of said housing, each adapted for propelling one of said missiles toward the co-ordinated tone element and having a distance from said element several times as large as the extension of said missile in the direction of propulsion whereby said propelled missile makes a move of considerable length from said projector to said element.
